UNITED STATES PATENT OFFICE.

CHARLES A. HATCH, OF HARTFORD, CONNECTICUT.

DESIGN FOR A CAR-FENDER.

SPECIFICATION forming part of Design No. 30,582, dated April 18, 1899.

Application filed August 17, 1898. Serial No. 603,091. Term of patent 7 years.

To all whom it may concern:

Be it known that I, CHARLES A. HATCH, a citizen of the United States, and a resident of Hartford, in the county of Hartford and State of Connecticut, have invented a new Design for Car-Fenders; and I do hereby declare the following, when taken in connection with the accompanying drawings and the letters of reference marked thereon, to be a full, clear, and exact description of the same, and which said drawings constitute a part of this specification.

This invention relates to a design for a car-fender used on the end of a railway-car; and the design consists of the configuration of the fender as described and shown in the accompanying illustration.

In the drawings, Figure 1 is a plan view of the fender. Fig. 2 is a view in side elevation, and Fig. 3 a perspective view.

The car-fender has a frame *a*, bent and curved in a vertical as well as a horizontal plane, the lower section extending forward beyond the plane of the back of the fender and showing a blunt rounded point *b* when viewed from the top.

The bar of material forming the frame is rounded in cross-section on its front and upper surface, and the opening bounded by this frame is quite closely filled with a grid of bars *c*, extending across the space from top to bottom of the frame.

Beginning at the point *b*, which when the structure is in its normal position for use is the lower and forward end, the frame extends 35 backward on opposite sides of a central vertical plane, flares outward until its greatest width is reached, the tangents *d d'* rounding into the compound curves *e e'*, in which the side parts of the frame extend inward, upward, and then forward to the reentrant curved part *f*, which completes the contour of the bounding-lines of the fender-frame.

The essential feature of my design consists in the top and bottom edges of the fender 45 projecting forward in practically parallel lines when viewed from the side, the bottom edge projecting farther than the top edge, the latter being evenly curved from side to side and the top and bottom edges being 50 joined at the rear on each side by a portion evenly curved from top to bottom.

I claim—

The design for a car-fender, substantially as described and shown in the accompanying 55 illustration.

In testimony whereof I have signed this specification in the presence of two subscribing witnesses.

CHARLES A. HATCH.
